UNITED STATES PATENT OFFICE.

GIBSON H. KENNEDY, OF CEDARTOWN, GEORGIA, ASSIGNOR, BY MESNE AND DIRECT ASSIGNMENTS, TO SONOCO PRODUCTS COMPANY, OF HARTSVILLE, SOUTH CAROLINA, A CORPORATION OF SOUTH CAROLINA.

CONE-WINDING MANDREL.

Application filed July 25, 1922. Serial No. 577,410.

To all whom it may concern:

Be it known that I, GIBSON H. KENNEDY, a citizen of the United States, and residing at Cedartown, Polk County, State of Georgia, have invented certain new and useful Improvements in Cone-Winding Mandrels, of which the following is a specification.

This invention relates to means for winding a sheet pattern of flexible material into the form of a cone, open at its ends and is particularly adapted for use in making, from corrugated paper, what are called cone tubes and which are extensively used in the textile industry. It consists principally in a novel construction of the cone winding mandrel whereby the formation of the cone may be accomplished with greater ease, quickness and efficiency producing more perfect and uniform cones than those made by devices heretofore used and making possible a machine wound cone with an inner feathered edge. One of the most important features consists in the gripping means carried by the conical mandrel between its ends for receiving and holding the edge of a sheet pattern which is being wound into cone form. It permits the use of a pattern having a thin straight edge extending for the full length of the mandrel and of the cone to be formed and which edge is gripped and held on said mandrel throughout its central longitudinal portion on a longitudinal line but is not gripped at its ends but having end portions beyond the gripping means closely fitting on the conical surfaces of the mandrel whereby after winding and while the cone is still gripped and held securely in position on the mandrel the ends of the cone may be cut off to produce smooth transverse end surfaces. The inner edge of the material forming the cone thus extends on a straight line entirely from one end of the cone to the other having no end portions cut away to form an intermediate tongue for gripping and thus the edge may be very thin, forming a practically perfect conical inner surface after completion, such as will fit the spindle on which the cone is used accurately from end to end. In the preferred form of the invention shown in the drawings, the gripping means, which engages the edge of

the sheet pattern, embodies a novel structure by which it performs the radically new and very advantageous function of pressing the previously gripped edge of the sheet smoothly against the inner surface of the adjacent layers of the cone pasting it to the other layers by a wiping action over the edge when said grip mechanism is moved to released position. The novel features of the invention will be more fully understood from the following description and claims, taken with the accompanying drawings.

In the drawings, Figure 1 is a side view partly in section of a cone winding mandrel and its supporting shaft, together with the elements of the mechanism for operating the means for clamping the sheet to be wound;

Figure 2 is a section on line 2—2 of Figure 1, with the parts in one rotary operative position;

Figure 3 is a similar view with the parts in a different rotary and operative position;

Figure 4 is a section on the line 4—4 of Figure 1, looking to the left;

Figure 5 is a longitudinal section of a mandrel embodying a modified construction; and,

Figure 6 is a cross section on the line 6—6 of Figure 5.

In the particular embodiment of the invention shown, for the purpose of illustration there is a mandrel 10 having a conical surface from the line 11 to the tip end 12 and it is carried on the end of the tubular rotary shaft 13 which is mounted in suitable bearing supports 14 and 15. The shaft 13 has screw threads 16 on its end which engage similar screw threads in a socket 17 in the base of the mandrel. Between the ends of the conical surface of the mandrel 10, there is a comparatively thin sleeve or collar 18, the outer surface of which forms part of the conical surface of the mandrel and this sleeve is rotatable to a limited extent on the mandrel. The mandrel is of course reduced in diametric size from the line 19 to the line 20, forming a longitudinal depressed portion, receiving and carrying the sleeve 18 around it. The sleeve or collar 18 has a longitudinal slot 21 therein, one edge 22 of that slot being slightly inclined from the inner surface of the sleeve

to the outer, while opposite edge 23 is curved inwardly from the outer surface. A solid rod or shaft 24 is concentrically mounted in the rotary tubular shaft 13 and extends into and fits a cylindrical socket 25 in the mandrel 10 and this rod 24 has secured to it a pin 26, projecting at right angles and connected at its outer end to the collar 18. This pin is in a transverse segmental slot 27, formed in the mandrel midway of the length of the collar 18 and this slot permits relative rotary movement between the shaft 25 and the collar 18, connected to it on the one hand and the mandrel on the other hand for a fixed distance. In other words, this relative movement is limited by the contact of the pin 26 with the ends of the slot, as shown in Figures 2 and 3. The outer surface of the mandrel, at the reduced portion under the collar 18 is further reduced in diametric size below the normal position of the slot 21 in the collar, on a plane parallel to a tangent, leaving straight line edges 28 and 29 making contact with the inner surface of the collar 18 as shown in Figure 3. The portions of the conical outer surface of the mandrel at the end of this last mentioned depressed portion and beyond the ends of the collar are depressed at 30 and 31 in line with the slot in collar 18, these depressions being on curved lines and for only a short distance longitudinally from the ends of the collar. The purpose of these depressions and the depression on the lines 28 and 29 is to permit the edge of a sheet of paper which is to be wound into cone form to enter the slot with its inner edge below the edge of the collar, whereby when the collar is relatively turned on the mandrel the edge 22 of the collar will make contact with the outer surface of the sheet 32 so as to grip it between the straight edge of the sleeve and the straight edge of the depression in the mandrel. It will be noted that the depressions 30 and 31 at the ends of the collar permit a sheet or pattern, having a straight edge extending longitudinally the length of the mandrel to be moved upwardly in Figure 1, for instance, in contact with the lower edge of the slot 21 and under the upper edge throughout the central portion while the end portions of the sheet edge will lie along the surface of the end portions of the mandrel and then the relative rotary movement of the sleeve on the mandrel, above indicated, will clamp it in position ready for winding. As will be seen by reference to Figures 1 and 3, the edge of the collar at the side of the slot 21 projects over the depressed portion between lines 28 and 29 and thus is in effect a comparatively thin tongue with its straight end edge longitudinally of the mandrel between the depressions 30 and 31.

In order to automatically hold the sleeve 18 in clamping position, gripping the sheet of paper being wound during the winding, yielding spring connection is provided between the tubular shaft 13 on which the mandrel is mounted and the solid shaft 24, rotatable with the collar tending to hold them in clamped position. It will be seen by reference to Figure 1 that there is a cup shaped member 33 having an outer cylindrical surface, fitting in the tubular shaft 13 and rigidly connected thereto by the screw 34 so as to rotate therewith. A similar cup-shaped member 35, having an outer cylindrical surface fits in the outer end of the tubular shaft 13 and projects therefrom a short distance and is connected to the shaft 24 which passes through its base by screw 36. These two cup-shaped members are, of course, formed of metal and the outer surface of member 15 forms a rotary bearing surface with the inner surface of the tube 13, whereas the opening in the base of member 33 forms a rotary bearing surface with the shaft 24. A coiled spring 37 surrounds the shaft 24 and extends from approximately the bottom of cup-shaped member 33 to the bottom of member 35 and is secured at 38 to member 33 and at 39 to member 35. This coiled spring is normally under tension, tending to rotate shaft 24 in a counter-clockwise direction in reference to shaft 13 and the mandrel 10 so that the pin 26, connecting shaft 24 to the sleeve 18 will normally be in the position shown in Figure 2 near the end of the slot with the edge 22 of the sleeve in clamping position, gripping the sheet 32 between it and the straight edge 29 of the depression in the mandrel. In other words this spring normally holds the gripping mechanism in position to hold the sheet being wound during and after winding and until it is positively released.

In the form shown, the shaft 24 may be positively turned to released position by the vertical movement of a toothed rack bar 40 which is adapted to engage, when moved upward, the teeth of gear wheel 41, mounted on the end of shaft 24 so as to turn that shaft according to the amount of upward movement given to the rack bar 40. That rack bar as shown in Figure 4 is normally below and out of mesh with the gear 41 so as not to interfere with the normal turning of that gear on the tubular shaft 13 and the mandrel 10 during the winding of the sheet in forming the cone. This rack bar is, of course, held and guided by suitable means 42 and may be given its vertical movement by any suitable means. In the particular form shown, there is a lever 43 pivoted to a fixed support at 44, having flexible connection at one end 45 to the lower end of the rack bar 40 and the other end having a roller 130

46 operated by a cam 47, driven in the usual way from the power which runs the machine in which it is placed. The cam, as shown, is of such shape that the rack bar 40 will remain in its lower position out of mesh during most of the rotation, but as the roller 46 rides up the inclined surface to the point the shaft 24 and the collar 18 will be turned in clockwise direction in reference to the 10 mandrel thus carrying the edge 22 from gripped position shown in Figure 2 continuously until pin 26 comes in contact with the end of the slot at the right in Figure 3 and the edge 23 of the slot moves upward 15 until it almost reaches the straight edge 28 of the depressed portion of the mandrel. It will be seen by reference to Figure 2 that this not only releases the end 32 of the sheet which was gripped during winding, but the 20 curved outer surface of the edge 23 of the sleeve by a wiping action, passes up along the inner surface of that end forcing it outward and tight against the inner surface of the cone which has been formed and since 25 that end has adhesive material on it the result will be to smoothly paste this edge of the material to the inner surface of the cone.

In starting the operation of winding a sheet into cone form, the sleeve 18 is brought 30 to such position that the slot in it will be in substantially midway position over the depressed portion of the mandrel whereby a sheet having a straight edge for the full length of the mandrel may be brought to position by a vertical movement when the parts 35 are arranged as shown and bending slightly inward the central portion so as to make its edge enter the slot and pass up behind its projecting edge 22, the depressions 30 and 31 at the ends of the slot permitting this movement while allowing the straight line edge 40 to lie along the outer surfaces of the conical mandrel beyond the ends of the sleeve. The sleeve is then released and under the action 45 of the spring 37 grips the edge of the sheet as shown in Figure 2, ready for winding. The means by which the straight edge of a blank to be wound into cone form may be brought to position by movement at right angles to its edge and will then be gripped 50 and held between its ends during and after winding is regarded as one of the important novel features of this invention, since it makes it possible to use a blank having a very thin edge which will extend on a straight longitudinal line from one end of the finished cone to the other on its inner surface. In other words it makes it possible 55 to form an inner feathered edge on the cone which makes its inner surface approximate that of an inner cone from one end to the other, whereas heretofore in machine made cones it was deemed necessary to have a tongue between the ends for the purpose of gripping during the winding where the ends 60

of the cones were to be cut off on the mandrel and this necessarily left a part of the edge cut away at each end leaving what might be called a vacant space which might interfere with the proper fit of the cone 70 on the spindle when used. Although in the specific form shown, this gripping mechanism by which this feathered edge is possible, embodies a separate sleeve which is rotatable on the mandrel, it will be noted that 75 the essential elements of that mechanism which makes possible the feathered edge cone, consists in the provision of a longitudinally straight edge between the ends of the conical surface of the mandrel with a depression in front of that edge and immediately beneath it and a slightly wider depression immediately beyond the ends of that straight edge so as to permit a part of a longitudinal straight edge of a sheet to enter beneath that edge and relatively movable means for cooperating with the under surface of the straight edge for clamping the edge of the sheet thereto. 80

In operation, the shaft 13 and the mandrel may be driven for winding the cone after the edge of the sheet has been placed in position thereon and clamped by any suitable means, for instance, by pulley 48 driven from any source of power and as 90 usual in machines for winding cones, may be made to automatically stop at the proper number of turns for the cones being made or the extent of the movement may, of course, be left to the control of the operator 95 by known means if desired. In the same way, the cam mechanism 47 and the lever 43 may be automatically controlled by the action of the machine as is well known in the art or by the physical action of the 100 operator by well-known means. In other words the invention does not consist in means for operating the mechanism shown but in the novel features of construction of that mechanism by which novel and useful results are accomplished. It will be further understood that the invention is not limited to the specific mechanism shown beyond what is called for in the claims. 110

In the form shown in Fig. 5 the conical mandrel 50 has a screw threaded socket 51 in its larger end adapted to receive and engage the end of a hollow rotary supporting shaft like 13 of Fig. 1. Extending inwardly and longitudinally of the mandrel 120 from the bottom of socket 51 there is a passageway 52 rectangular in cross section which slidably receives the clamp operating rod 53. This operating rod is rectangular 125 in section fitting the walls of the passageway 52 but one surface 54 at its inner end is inclined inward at a slight angle and this inclined surface portion is not of full width as is shown in Fig. 6. Side grooves 55 are formed slightly below and parallel to said 130

inclined surface and extend throughout its length terminating in open ends and forming the inclined guide ribs 56. The conical surface of the mandrel 50 at material distances from its ends has spaced depressed portions 57 and 58 inclined towards each other and at and between their inner ends there is a socket 59 rectangular in longitudinal and cross section extending inwardly to and joining the inner end portion of passageway 52. Extending laterally over this socket 59 from one side between the ends of the depressed portions there is a comparatively thin tongue portion 60 having a free edge 61 on a straight line and its outer surface being a part of the conical surface of the mandrel. The surface of the mandrel immediately in advance of said edge is slightly depressed at 62 permitting the central portion of a straight line edge of a sheet to pass laterally under it. A gripping member 63 which is rectangular in cross section fits in socket 59 below the tongue 61 and rests on the inclined end portion 54 of the operating rod 53, and is of substantially the same width as the main body of rod 53. It however, has between its ends side portions 64 extending inwardly across the ribs 56 and having inturned end portions 65 fitting in slots 55 so as to make a sliding tongue and groove connection between it and the operating rod 53. Since the sides and ends of member 63 make sliding contact with the sides and ends of socket 59 any movement of shaft 53 longitudinally of the mandrel will positively move it outwardly or inwardly because of the inclined sliding tongue and grooves connection. It will be noted that the clamping member 63 has a straight edge parallel to and on the inner side of the straight edge of tongue 61 and that those two edges may separate or come together by relative movement thus clamping the edge of a sheet between them or releasing it according to the direction of movement. This form like that of Fig. 1 permits the use of a sheet pattern having a full length straight line edge the central portion of which enters below tongue 61 and is securely clamped and held during and after winding so that the completely wound cone may have its rough ends severed smoothly and accurately by a cutting edge pressing inwardly on it towards the mandrel while the cone and mandrel rotate so that the finished cone may have an inner feathered edge.

Having thus described my invention, what I claim and desire to secure by Letters Patent is:

1. A device for winding a flexible sheet into the form of a cone comprising a mandrel having a conical outer surface on which the sheet winds the end portions of said mandrel being continuous circularly and a gripping mem-

ber extending longitudinally between said end portions only having its outer surface in the lines of the conical surface of the mandrel and having slight relative rotary movement thereon to cooperate with the mandrel in gripping the central portion of the edge of the sheet or releasing it and means extending through the end of the mandrel for operating said gripping member to cause the relative rotary movement in either direction. 70

2. A device for winding a flexible sheet into the form of a cone comprising a mandrel having a conical outer surface on which the sheet winds the end portions of said mandrel being continuous circularly and a gripping member extending longitudinally between said end portions only having its outer surface in the lines of the conical surface of the mandrel and having slight relative rotary movement thereon to cooperate with the 75 mandrel in gripping the central portion of the edge of the sheet or releasing it and means extending through the end of the mandrel for operating said gripping member to cause the relative rotary movement in either direction, 80

the said gripping member having a surface portion which by relative rotary movement in releasing the grip on the sheet edge will by a wiping action press said edge outwardly smooth against the inner surface of the tube. 95

3. A device for winding a flexible sheet into the form of a cone comprising a mandrel having a conical surface on which the sheet winds, the end portions of said mandrel being continuous circularly and releasable gripping means between said end portions only for laterally receiving, engaging and holding a straight edge of said sheet on a straight line longitudinally of said mandrel between the said portions and between the 100 ends of the straight edge of said sheet whereby the ends of the cone beyond said gripping means may be cut on straight transverse lines on a continuous supporting surface while held securely in position on the mandrel. 105

4. A device for winding a flexible sheet into the form of a cone comprising a mandrel having a conical surface on which the sheet winds the end portions of said mandrel being continuous circularly having materially greater length than the finished cone and releasable gripping means between said end portions only on a longitudinal line for engaging and holding the central portion only of one edge of said sheet of full length during winding whereby the ends of said sheet when wound may be cut off on straight transverse planes while the cone is held securely in position on the mandrel. 115

5. A device for winding a flexible sheet into the form of a cone comprising a mandrel having a conical surface on which the sheet winds, the end portions of said mandrel being continuous circularly, having ma- 120

terially greater length than the finished cone and releasable gripping means between said end portions only on a longitudinal line for engaging and holding the central portion 5 only of one edge of said sheet of full length during winding whereby the ends of said sheet when wound may be cut off on straight transverse planes while the cone is held securely in position on the mandrel, the said 10 gripping means having a surface which when moved from gripping to released position will by an ironing action, smoothly paste the previously gripped edge to the interior surface of the tube.

15 6. A device for winding a flexible sheet into the form of a cone comprising a mandrel having a conical surface on which the sheet winds, the end portions of said mandrel being continuous circularly and releasable gripping means between said end portions only for laterally receiving, engaging and holding the edge of said sheet on a line extending longitudinally of said mandrel, the said gripping means having a surface 20 which will, by movement after release from gripping position, paste the previously gripped edge smoothly to the interior surface of the cone by an ironing action.

25 7. A device of the class described, for winding paper cone tubes, comprising a mandrel having aligned longitudinally spaced conical end portions rigidly connected together by a conical portion of reduced diameter and a conical cuff or collar fitting said portion of reduced diameter between said end portions, its outer surface forming with said end portions practically a continuous cone having a longitudinal slot therein, means for causing 30 rotary movement of said collar on said mandrel within fixed limits in opposite directions, the said central portion having at one part of its periphery an inwardly depressed portion having straight longitudinal side edges, across which depression the slot in the 35 sleeve is adapted to pass whereby the straight edge of a sheet of paper may be inserted in the slot when it is over the depressed portion, and that edge will be caught between an edge or tongue of the collar forming the 40 slot and an edge of the longitudinal depression on relative rotation of the sleeve and mandrel.

45 8. A device of the class described, comprising a conical mandrel having thereon a collar between its ends which forms part of the conical surface and which has a longitudinal slot therein, means for rotatively moving said collar on said mandrel within fixed limits, means permitting the 50 edge of a sheet of flexible material to enter through said slot in one position and to extend a short distance along its inner surface and means on said mandrel within said collar cooperating with one edge of 55 said collar throughout its length to clamp

and hold the entering edge of said sheet when the collar is turned in one direction on the mandrel.

9. A device of the class described, comprising a conical mandrel having thereon a collar between its ends which forms part of the conical surface and which has a longitudinal slot therein, means for rotatively moving said collar on said mandrel within fixed limits, means permitting the 70 edge of a sheet of flexible material to enter through said slot in one position and to extend a short distance along its inner surface and means on said mandrel within said collar cooperating with one edge of 75 said collar throughout its length to clamp and hold the entering edge of said sheet when the collar is turned in one direction on the mandrel and automatic yielding means for maintaining the collar and 80 mandrel in clamping position.

10. A device of the class described for winding paper cone tubes, comprising a conical mandrel of greater length than the tube to be wound having thereon a cuff or collar between its ends of slightly less length than the tube to be wound, which forms part of the conical surface and which has a narrow longitudinal slot therein for 85 the entry of the edge of the sheet to be wound, means for rotatively moving said collar on said mandrel within fixed limits, means rigid with said mandrel cooperating with one edge of said collar to grip and 90 securely hold the edge of said sheet throughout the length of said collar when said collar is turned to proper position in one direction.

11. A device of the class described for winding paper cone tubes, comprising a conical mandrel of greater length than the tube to be wound having thereon a cuff or collar between its ends of slightly less length than the tube to be wound, which forms part of the conical surface and which has a narrow longitudinal slot therein for 95 the entry of the edge of the sheet to be wound, means for rotatively moving said collar on said mandrel within fixed limits, means rigid with said mandrel cooperating with one edge of said collar to grip and 100 securely hold the edge of said sheet throughout the length of said collar when said collar is turned to proper position in one direction and automatic means for yieldingly holding the parts in clamping position during winding.

12. A device of the class described for winding paper cone tubes, comprising a conical mandrel of greater length than the tube to be wound having thereon a cuff or collar between its ends of slightly less length than the tube to be wound, which forms part of the conical surface and which has a narrow longitudinal slot therein for 115 120 125 130

- the entry of the edge of the sheet to be wound, means for rotatively moving said collar on said mandrel within fixed limits, means rigid with said mandrel cooperating with one edge of said collar to grip and securely hold the edge of said sheet throughout the length of said collar when said collar is turned to proper position in one direction and automatic means for 10 yieldingly holding the parts in clamping position during winding, the outer surface of the other edge of said slot being peripherally curved inward from circular lines so as to present a rounded surface to engage and press the previously clamped edge of the sheet outwardly against the inner surface of the cone when the collar is given a reverse rotary movement releasing the clamp.
13. A device of the class described for winding paper cone tubes, comprising a conical mandrel of greater length than the tube to be wound, having thereon a cuff or collar between its ends of slightly less 25 length than the tube to be wound, which forms part of the conical surface and which has a narrow longitudinal slot therein for the entry of the edge of the sheet to be wound, means for rotatively moving said 30 collar on said mandrel within fixed limits, means rigid with said mandrel cooperating with one edge of said collar to grip and securely hold the edge of said sheet throughout the length of said collar when said 35 collar is turned to proper position in one direction, the width of the slot and the extent of rotary movement permitted being such that in the reverse movement of the collar on the mandrel its other edge will 40 progressively move to and beyond the edge of the sheet pressing said edge smoothly against the inner surface of the cone.
14. A cone winding device comprising a rotatable conical mandrel reduced in size at 45 its central portion with substantial uniformity throughout most of its periphery but having an inwardly depressed portion between adjacent longitudinal lines, a collar surrounding said reduced portion and extending throughout its length with its outer surface forming a connecting continuation of the conical end surfaces of the mandrel and having a longitudinal slot therein, a central shaft extending into said mandrel 50 from its base and having thereon a lateral extension connected at its outer end to said collar and adapted to move in a slot in said mandrel in a rotary direction to a limited extent which permits the collar to rotate on the mandrel sufficiently to carry its slot substantially across said depressed portion of the mandrel in either direction.
15. A cone winding device comprising a rotatable conical mandrel reduced in size 55 at its central portion with substantial uniformity throughout most of its periphery but having an inwardly depressed portion between adjacent longitudinal lines, a collar surrounding said reduced portion and extending throughout its length with its outer surface forming a connecting continuation of the conical end surfaces of the mandrel and having a longitudinal slot therein, a central shaft extending into said mandrel from its base and having thereon a lateral extension connected at its outer end to said collar and adapted to move in a slot in said mandrel sufficiently to carry its slot substantially across said depressed portion of the mandrel in either direction.
16. A cone winding device comprising a rotatable conical mandrel reduced in size at its central portion with substantial uniformity throughout most of its periphery but having an inwardly depressed portion between adjacent longitudinal lines, a collar surrounding said reduced portion and extending throughout its length with its outer surface forming a connecting continuation of the conical end surfaces of the mandrel and having a longitudinal slot therein, a central shaft extending into said mandrel from its base and having thereon a lateral extension connected at its outer end to said collar and adapted to move in a slot in said mandrel in a rotary direction to a limited extent which permits the collar to rotate on the mandrel sufficiently to carry its slot substantially across said depressed portion of the mandrel in either direction, a hollow cylindrical rotary shaft surrounding said central shaft throughout a part of its length connected to said mandrel at one end and mounted in stationary bearings.
17. A cone winding device comprising a rotatable conical mandrel reduced in size at its central portion with substantial uniformity throughout most of its periphery but having an inwardly depressed portion between adjacent longitudinal lines, a collar surrounding said reduced portion and extending throughout its length with its outer surface forming a connecting continuation of the conical end surfaces of the mandrel and having a longitudinal slot therein, a central shaft extending into said mandrel from its base and having thereon a lateral extension connected at its outer end to said collar and adapted to move in a slot in said mandrel sufficiently to carry its slot substantially across said depressed portion of the mandrel in either direction.

- tially across said depressed portion of the mandrel in either direction, a hollow cylindrical rotary shaft surrounding said central shaft throughout a part of its length connected to said mandrel at one end and mounted in stationary bearings, a coiled spring under tension in said hollow shaft connected at one end to said hollow shaft and at the other end to said central shaft tending to hold the collar and mandrel in clamping position, movable means adapted to act on the projecting end portion of the central shaft to turn said sleeve to release position on said mandrel.
18. A device for winding a flexible sheet into the form of a cone comprising a mandrel having a conical outer surface on which the sheet winds, gripping means between the end portions of said conical surface including a comparatively thin tongue having a straight longitudinal end edge the outer surface of which is in the lines of the conical mandrel the material of the conical surface being depressed from the ends of said tongue edge longitudinally for a short distance whereby the central portion of the straight edge of a sheet of full length may be inserted under said straight edge by a movement of said sheet at right angles to said edge and means adapted to clamp said sheet edge to the under surface of said tongue edge.
19. A device for winding a flexible sheet into the form of a cone comprising a mandrel having a conical outer surface on which the sheet winds, gripping means between the end portions of said conical surface including a comparatively thin tongue having a straight longitudinal end edge the outer surface of which is in the lines of the conical mandrel the material of the conical surface being depressed from the ends of said tongue edge longitudinally for a short distance whereby the central portion of the straight edge of a sheet of full length may be inserted under said straight edge by a movement of said sheet at right angles to said edge and means adapted to clamp said sheet edge to the under surface of said tongue edge and yielding means for holding it in clamped position.
20. A device of the class described for winding paper cone tubes, comprising a conical mandrel of greater length than the tube to be wound having thereon a cuff or collar between its ends of slightly less length than the tube to be wound, which forms part of the conical surface and which has a narrow longitudinal slot therein for the entry of the edge of the sheet to be wound, the surface of said mandrel at the ends of said slot being depressed for a short distance longitudinally to permit the central portion of the full length straight edge of the sheet to be wound to enter laterally the slot and lie under its edge while the end portions of said sheet edge lie on the conical end portions of the mandrel, means for rotatively moving said collar on said mandrel within fixed limits, means rigid with said mandrel cooperating with one edge of said collar to grip and securely hold the edge of said sheet throughout the length of said collar when said collar is turned to proper position in one direction.
21. A device of the class described for winding cones from a flexible sheet comprising a mandrel having a conical outer surface and gripping means along the central longitudinal portion of said conical surface between its end portions for laterally receiving and securely holding thereon the central portion of a straight edge of said sheet extending beyond the ends of said gripping means longitudinally of said conical surface.
22. A device for winding a flexible sheet having straight edges into the form of a cone, comprising a mandrel having a conical surface on which the sheet winds, the end portions of said mandrel having outer surfaces which are continuous circularly, and gripping means extending longitudinally of the mandrel between said end portions only, adapted to receive, engage and hold the central portion only of a straight edge of said sheet when said edge is moved laterally into gripping position, the said gripping means engaging said edge with substantial uniformity throughout the length of said gripping means.

In testimony whereof I hereunto affix my signature.

GIBSON H. KENNEDY.
